UNITED STATES PATENT OFFICE.

LOUIS KOVACS, OF CHICAGO, ILLINOIS.

COMBINATION-SWITCH.

1,310,354.

Specification of Letters Patent.

Patented July 15, 1919.

Application filed January 21, 1918. Serial No. 212,930.

To all whom it may concern:

Be it known that I, LOUIS KOVACS, citizen of Austria-Hungary, residing at Chicago, in the county of Cook and State of Illinois, have invented certain new and useful Improvements in Combination-Switches; and I do hereby declare the following to be a full, clear, and exact description of the invention, such as will enable others skilled in the art to which it appertains to make and use the same.

In its general aspects, my invention relates to combination switches; that is to say, switches in which the circuit is controlled at a number of different points and in which the switching members for making the connections at all of these different points must be in their proper positions to jointly close the circuit. In some of its more particular aspects, my invention relates to a combination or secret switch having several switching members arranged so that their respective positions will be indicated on exposed dials without indicating whether or not these switching members are in position for closing their particular portions of the circuit; to provide an unusually simple and effective construction of such a switch which will enable the same to be manufactured and assembled cheaply, and which will readily permit the switches to be assembled according to a wide range of different dial indications or combinations without requiring alterations in the manufactured parts.

In another aspect of my invention, it aims to provide a novel type of secret switching means which may be desirably connected in series with the dial-indicated switching portions of a combination switch, which will be easily manufactured and assembled, and which will be operable by a sliding contact without uncertainty and while continuously concealing its mechanism from view. Still other and to some extent more detailed objects will appear from the following specification and from the accompanying drawings, which drawings show my invention as embodied in a switch adapted to be fastened to the dash-board of an automobile for controlling the ignition circuit.

In the drawings, Figure 1 is an elevation of this embodiment.

Fig. 2 is an axial section through the same,

taken along the line 2-2 of Fig. 1 and also including in diagrammatic form the battery and spark plug connections for such a switch.

Fig. 3 is a transverse section through the switch, taken along the zigzag line 3-3 of Fig. 2.

Fig. 4 is a fragmentary and enlarged section through one pair of the contacts forming part of the switching mechanism.

Fig. 5 is a transverse section taken through Fig. 2 along the line 5-5.

Fig. 6 is an enlarged section through a part of Fig. 5 along the line 6-6.

Fig. 7 is a partially diagrammatic longitudinal section through another embodiment of my switch, showing an alternative arrangement of the rotatable switch blades, numerous parts of the switching being omitted to simplify the drawing.

Fig. 8 is a section similar to a portion of Fig. 6 and showing another arrangement of the wire terminals.

One important part of my switch is that relating to the independently rotatable switching arms and the circuit portions controlled thereby. In the embodiment of Figs. 1, 2 and 4, the casing 1 of this switch and the base 2 mounted in this switch jointly form bearings for a shaft, which shaft gradually decreases in diameter from a head 3 at its outer end to a stem 4 pivoted in the base 2 and locked to the latter in any suitable means, such as a washer 5 pinned to this stem. Adjacent to the stem 4, the shaft of the switch has a square portion 6 fitting a corresponding portion in an insulator 7 which has at one end a somewhat larger square portion interlocking with a square opening in a switching blade 8. Near its head end, the said shaft has a still larger square shaft 9 fitting a corresponding opening in a pointer member 10 which moves over a graduated dial 11 and thus affords an indication of the position of the contact member. The portion of the shaft between the larger square shank 9 and the smaller square portion 6 is preferably round and extends both through an insulating washer 12 and an externally square tube 13. This latter tube fits the angular bore of an insulating bushing 14 which has a square portion fitting an aperture in a longer contact member 15, while the square exterior

100

105

of the tube 13 fits the aperture of a longer pointer member 16, which pointer moves over a larger dial 17 and thereby gives an indication of the position of the contact 5 member 15.

Each of the said contact members has a tip portion bearing resiliently against the inner surface of the base 2, and each of these contact members is adapted at some point in 10 its rotational movement to afford the connection between two relatively spaced contacts which are connected to portions of the circuit controlled by the switch. These contacts may desirably be in the form of hol- 15 low screws 17 and 18 as shown in Fig. 4, each of which screws has its head embedded substantially flush with the inner surface of the base 2 and has a tip of one of the circuit wires soldered into its bore. With this ar- 20 rangement, it will be obvious from the drawing that the contact portion of my switch can be very cheaply constructed and that with a given boring of the holes into which the screws 17 and 18 are threaded, and a given 25 mounting of these on the shaft, four different dial indications can be secured for each contact member by successively shifting the pointer members a quarter turn with respect to the square-sectioned portions with 30 which the latter are interlocked. Likewise, each of the contact members can be placed in four rotationally different positions with respect to the square bushing portions with which it is interlocked, so that I can obtain 35 a large number of different combinations without altering the position of the pairs of contact screws with respect to the cover on which the dials are engraved or mounted. Then I can further increase this range of 40 combinations by fastening the base 2 in a series of rotationally different positions within the casing. For this purpose I need only provide the base 2 with a series of notches 19, one of which is entered by a 45 screw 20 extending through a side of the casing, it being obvious from Fig. 3 that by turning the base 2 to bring one after another of the notches 19 opposite the screw 20 I correspondingly vary the dial indications 50 for their given position for the contact members with respect to the base 2.

However, even with the large number of possible combinations thus secured by my construction, it might be possible for a 55 stranger to find the combination by a systematic series of manipulations. That is to say, he might set the longer pointer successively on one after another of the corresponding dial markings, and then turn the 60 smaller knob 21 on the shaft of the switch so as to completely rotate the shorter contact member. In this manner, he would gradually cover the range of combinations possible with the base of the switch in any 65 given position, this being the kind of ma-

nipulations which have spoiled the intended safe-guarding feature of combination switches as heretofore devised for protecting automobiles. To prevent such an occurrence, I preferably provide an auxiliary 70 switch portion connected in series with both of the pairs of contact screws and also arranged with markings which indicate the needed position of this part of the switch. Such auxiliary portion is desirably mounted 75 also within the casing of the switch and desirably built in the shape of a slide. For example, the tip of the series 22 and 23 may be disposed in grooves extending parallel to the shaft of the switch and notched into the 80 concentric channel walls of an insulator 24 fastened in any suitable means to the casing 2 near its closed end. The said channel forms a raceway for a metal collar 25 mounted on an insulator 26, which insulator may 85 be moved by means of a handle 27 extending through a relatively narrow slot 28 in the closed or cover end of the casing. With the wire tips 22 and 23 disposed substantially 90 flush with the inner walls of the said raceway, it will be obvious from Figs. 5 and 6 that the metal collar 25 will electrically connect these wires only when this collar is in a certain position, which position can be seen from auxiliary dial markings 29 on the 95 surface of the casing.

To prevent the position of the wires 22 and 23 from being seen through the slot 29, I provide a grooved strip 30 which is mounted on the handle 27 and disposed inside the 100 cover portion of the casing, and which is considerably longer than the slot 28, so as to continuously close the latter to the observer. Thus constructed, this slide portion in itself forms a switch with concealed contacts, and while it might be possible to also 105 position the handle 27 successively opposite each of the markings on the dial 29 and to try out all of the possible positions of the pointers 10 and 16 for each of these dial 110 indications 29, it will be obvious that any such effort would require an amount of time not available under any ordinary circumstances. Consequently, by this simple and baffling addition to a two-dial combination 115 switch, I can produce an appliance which will far more effectively safeguard a given circuit than has heretofore been possible. In using a switch of my invention, I desirably connect the various pairs of contact 120 portions (namely both pairs of the contact screws 17 and 18 as well as the tips of the wires 22 and 23) in series with each other. For example, Fig. 2 shows such connections as controlling the circuit from a battery 31 125 to a spark plug 32. However, I do not wish to be limited to these particular connections or particular uses of my invention, nor to the various details of the construction and arrangement here described, it being obvious 130

that the same might be modified in many ways without departing from the spirit of my invention. For example, instead of placing the contact screws 17 and 18 adjacent to each other, and longitudinally connecting them by the single tip of a contact member, I might place these screws opposite each other with respect to the shaft of the switch, using double ended contact members as shown in Fig. 7. Or, instead of using the wire tips themselves for making direct contact with the slidably mounted collar 25, I may clamp the wire tips under screws 32 and 34 having reduced shanks extending flush with the inner surfaces of the channel-sectioned insulating body 24, as in Fig. 8.

I claim as my invention:

1. A secret switch including contact-making members rotatable about a common axis, and means for supporting and rotating the said contact members; said means comprising a pair of insulating washers each interlocked with one of the contact members, a spacer washer disposed between the aforesaid washers and serving to clamp the said contact members to the washers to which they are respectively interlocked, a tubular shaft having an angularly sectioned exterior interlocked with one of the first named washers, a second shaft extending through the tubular shaft and all three of the washers and having an angularly sectioned portion interlocked with the other of the first named washers; stationary contacts disposed for contacting respectively with the said contact members when the latter are in predetermined positions, and means connected respectively to the two shafts for indicating the positions of the said contact members.

2. Switch construction as per claim 1, in which the contact members are adapted to be secured in a number of different positions with respect to the axis of the shaft, thereby changing the relative position of these con-

tact members with respect to the indicating means.

3. Switching mechanism as per claim 1, in which both the contact members and portions of the indicating means are each adapted to be secured to the shaft portions with which they are associated in a plurality of different positions, thereby effectively changing the indications afforded by the indicating means.

4. Switch mechanism as per claim 1, in which the means for securing the contact members and indicating means to the shaft portions with which they are associated include polygonal bores in certain of the said members and male portions on other members interlocked with the said bores, and in which the bore associated with each contact member is twisted with respect to the bore of the indicating means associated with the same contact member, so that the flattened surfaces of the said bores are angularly out of alinement.

5. In a secret switch, a substantially cup-shaped casing, an insulating base disposed therein and rotatable with respect to the casing and having a plurality of notches on its periphery; a plurality of wire terminals mounted on the insulating base and disposed in pairs arranged substantially radially of the common axis of the base of the casing; relatively insulated contact blades arranged for contacting respectively with the said pairs of wire terminals; rotating and indicating means associated respectively with the contact blades and arranged for affording indications upon the exterior of the casing, and means for interlocking a lateral portion of the casing with any one of the notches in the insulating base, thereby permitting the insulating base to be fixed in any one of several angular positions with respect to the casing.

Signed at Chicago, Illinois, January 12th, 1918.

LOUIS KOVACS.
